(57) **CLAIM**

The ornamental design for a sled construction with pontoons, as shown and described.

DESCRIPTION

FIG. 1 is a perspective view of the sled construction with pontoons as constructed in accordance with the present invention;

FIG. 2 is a top plan view of the sled construction with pontoons of FIG. 1;

FIG. 3 is a bottom plan view of the sled construction with pontoons of FIGS. 1 and 2;

FIG. 4 is a left-side view of the sled construction with pontoons with the right-side view being a mirror image of FIG. 4;

FIG. 5 is a front end view of the sled construction with pontoons taken from the left of FIG. 2; and,

FIG. 6 is a rear end view of the sled construction with pontoons taken from the right of FIG. 2.
